B. C. GUSE

SELECTOR VALVE

Filed Feb. 27, 1922

J. L. Fox.

Bernard C. Guse, INVENTOR

BY *Victor J. Orman.*
ATTORNEY

ATTORNEY

WITNESS:

UNITED STATES PATENT OFFICE.

BERNARD C. GUSE, OF SANBORN, IOWA.

SELECTOR VALVE.

Application filed February 27, 1922. Serial No. 539,786.

To all whom it may concern:

Be it known that I, BERNARD C. GUSE, a citizen of the United States, residing at Sanborn, in the county of O'Brien and 5 State of Iowa, have invented new and useful Improvements in Selector Valves, of which the following is a specification.

This invention relates to improvements in dispensing systems especially designed for 10 dispensing oil and the like at automobile service stations.

An object of the present invention is the provision of means whereby a plurality of tanks or containers may be connected to a 15 common source of air supply, to dispense different grades of oil or other fluid under pressure, provision being made for controlling the air to each individual tank.

Another object of the invention is the provision of a novel dispensing valve for discharging the contents from the containers through a single discharge spout, means being included in the valve for selectively controlling the discharge from any one of the 25 individual containers.

With the above and other objects in view, the invention further includes the following novel features and details of construction, to be hereinafter more fully described, illustrated in the accompanying drawings and 30 pointed out in the appended claim.

In the drawings:

Figure 1 is a section taken on line 1—1 of Figure 3.

Figure 2 is a top plan view of the valve.

Figure 3 is a side elevation of the same.

Figure 4 is a sectional view on the line 4—4 of Figure 1.

Referring in detail to the drawings, 40 wherein like characters of reference denote corresponding parts, the dispensing system is designed to include a plurality of tanks or liquid containers for the purpose of dispensing various grades of oil, or other liquid, the said tanks may contain light, medium and heavy oils.

Each of the tanks is supplied with a separate discharge pipe 22, 23 and 24 respectively and these pipes are in communication 50 with a valve casing 25, through which liquid from one of the containers may be dispensed. For this purpose, the valve casing 25 is provided with a single discharge nozzle 26. This nozzle is controlled by a plug valve 27 having a port or passage 28

therethrough and also having an operating handle or wheel 29, the said valve having its lower end reduced and bearing within an opening 30 provided in the casing 25.

Also located within the casing 25 is a selector valve 31, this valve being provided with an opening 32 formed in a circular head 33. The opening 32 provides an additional bearing for the plug valve 27, while the head 33 within which this opening is formed has a bearing as at 34 in the casing 25. The opposite end of the valve 31 is provided with an arcuate head 35 which is adapted to bear against the inner wall of the casing 25 and to close inlet ports 36, 37 and 38 provided in the valve casing. These inlet ports are in communication respectively with the discharge pipes 22, 23 and 24. The valve 31 is provided with a passage 39 which is adapted to be brought into register with any one of the ports 36, 37 or 38 and the port 28 provided in the plug valve 27. Communication may thus be established between any one of the inlet ports of the valve casing and the discharge spout 70

26. The selector valve 31 is capable of operation independently of the plug valve 27 and for this purpose is provided with a handle 39', by means of which it may be rotated within the bearings 34 of the casing 80 and around the plug valve 27. In order to hold the valve member 31 in proper position there is provided a plurality of notches 40, which are engageable by a spring actuated dog 41 carried by the handle 39'. This dog 90 is formed in separate sections and includes a notch engaging tooth and a separable shank 42, the latter operating within the bore formed in the handle 39' and being engaged by a spring 43. Secured to the handle 39' of the valve 31 is a pointer 44 which is movable with the valve, while the top of the valve casing 25 contains suitable indicia for co-operation with the pointer to indicate the particular tank or container 100 from which liquid is to be discharged. These indicia are shown in Figures 1 and 2 of the drawings and include L for light, M for medium and H for heavy, thus indicating different grades of lubricating oil.

In order to keep the plug valve 27 properly seated there is secured to the selector valve 31 a spring arm 45, whose outer end is provided with an opening for the reception of the stem of the valve 27 and this end 110

is adapted to bear upon the upper end of the said valve to yieldingly force the latter within its seat.

In addition, the invention provides a support 5 port for a suitable measure (not shown) into which liquid from the tanks or containers may be received. This support consists of a basin-like receptacle 46 having a strainer 47 spaced from the bottom thereof. This 10 strainer is provided with a reinforcing grating 48 and is located directly beneath the discharge spout 26 so that a measure or other receptacle may be supported thereon. The basin 46 is secured to the bottom of the 15 valve casing 25 by means of a depending arm or bracket 49.

It will be seen from the foregoing description and accompanying drawings, when it is desired to dispense liquid from the 20 tank containing light oil, the pointer 44 is directed toward the L on the valve casing 25. This will position the selector valve 31 so that the passage 39 establishes communication between the inlet port 36 and the outlet port or nozzle 26, the plug valve 27 being then operated to complete this communication. As long as the selector valve 31 remains in this position, the plug valve 27 25 may be operated to dispense liquid from the tank 10. Liquid from either the tank 11 or 30 12 may be dispensed by arranging the valve

31 in accordance with the letters M or H upon the valve 25.

The invention is susceptible of various changes in its form, proportions and minor details of construction and the right is herein reserved to make such changes as properly fall within the scope of the appended claim.

Having described the invention what is 40 claimed is:—

A valve comprising a casing having an arcuate wall, a plurality of inlet ports in said casing and leading through said wall and also having an outlet port, a turn valve 45 having an opening therein and also having its lower end reduced and bearing within an opening provided in the casing, an operating handle secured to the turn valve, a swinging selector valve mounted within the 50 casing and having an apertured circular head in which the turn valve is journaled and also having an arcuate shaped head bearing against the arcuate wall of the casing adjacent the inlet ports said swinging selector valve further having a central passage therein which communicates with the inlet ports and turn valve respectively and an operating handle on said selector valve.

55 In testimony whereof I affix my signature.

BERNARD C. GUSE.
